RAZOR BLADE HOLDER

Frank B. Shepard and Neal D. Shepard,
Texon, Tex.

Application December 4, 1945, Serial No. 632,627

2 Claims. (Cl. 30—330)

1

This invention relates generally to the class of cutlery and pertains particularly to improvements in blade holding devices or handles and particularly a handle for holding a double-edged razor blade.

A principal object of the present invention is to provide a blade holder for a double-edged safety razor blade wherein the blade will be effectively held in a prescribed position so that it may be readily sharpened by stropping or it may be used for cutting purposes so that the holding device or handle together with the removable blade provides a convenient knife.

Another object of the invention is to provide a safety razor blade holding device or handle which is formed of two relatively long members disposed in superimposed relation and pivotally coupled together substantially midway between their ends, the portions of the two long members at one end forming together a convenient hand grip while the portions at the opposite end are substantially interlocked and securely maintain the blade in a position where a relatively narrow portion along one cutting edge is exposed for use.

Still another object of the invention is to provide a device of the character described wherein novel means is employed for facilitating the ready pivotal movement of one member relative to the other for opening and releasing the blade holding portion.

Still another object of the invention is to provide a double-edged safety razor blade holder of the character stated wherein novel means is employed for releasably holding the two portions of the holder in blade holding position, such holding means being made effective by the inherent resiliency of the superimposed members to releasably hold such members in blade holding or in closed position.

The invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from the salient features of the invention as expressed in the appended claims.

In the drawing.

Figure 1 is a view in side elevation of the blade holder forming the present invention.

Figure 2 is a sectional view taken substantially

2

on the line 2—2 of Figure 1 with said portions not falling within the line of section, broken away to show details of construction.

Figure 3 is a transverse section taken substantially on the line 3—3 of Figure 1.

Referring now more particularly to the drawing it will be seen that the blade holding device comprises essentially the two relatively long members 10 and 11 which when in blade holding position are disposed one upon and parallel with the other.

One of the members, here shown as the member 10, is of greater length than the other and is thickened at the head end as indicated at 12, which thickened portion has the inner edge 13 thereof extending obliquely across the portion 10 and undercut as illustrated in Figure 2.

Substantially midway between the ends of the two members 10 and 11, the members are permanently coupled together by the pivot element 14 which is here shown as being in the form of a rivet having the ends flush with the outer sides of the two members which it couples together. This pivot element divides the blade holder into a head portion which is generally designated 15 and a hand grip portion which is generally designated 16.

As illustrated the head portion 15 has the two halves of which it is made up and which are designated 10' and 11', parallel at their opposing faces and tapered upon the outer faces so that the back edges of the two portions 10' and 11' are of greater thickness as indicated at 10'' and 11'' than they are at the forward edges thereby making the entire head portion 15 of greater thickness at the back and gradually decreasing thickness toward the forward edge. At the forward edge of the head the two portions 10' and 11' have their inner corners rounded as indicated at 17 and 18 and the forward edge of the portion 10' is provided with the two recesses 19 while the adjacent face of the portion 11' carries the two lugs 20 which are spaced to enter the recesses 19 and are also spaced and suitably formed to enter the slots or openings 21 which are commonly provided in double-edged safety razor blades, such, for example, as a safety razor blade of the Gillette type.

As shown in Figure 1 the portions 10' and 11' are of greater width than the two portions of the members 10 and 11 making up the hand grip 16 but the excess width of the portions 10' and 11' is entirely at one edge, that is, the forward edge, of the device so that the line of the

blade holder at the back edge is straight from one end of the device to the other.

The two portions of the device making up the hand grip 16 are designated 16a and 16b and each of these portions has secured thereto upon its outer face, a handle plate 22.

At their outer ends the handle portions are cut off obliquely along the lines 23, the oblique edge of one portion being disposed oppositely to the oblique edge of the opposite portion so that there are thus formed the tapered tail pieces 24 which, when gripped at their opposite edges between the fingers, may be pressed together to effect the pivotal movement of the two members 10 and 11 on the pivot 14, thereby bringing about a separation of the head portions 10 and 11 and the opening of the head for the insertion of a blade between such head portions.

One of the handle portions, here shown as the portion 16a, is provided upon its inner face and at its longitudinal center, with a shallow depression or recess 25 of circular form while the opposing portion carries the relatively flat button 26 upon its inner face, which is adapted to enter the recess 25 when the two handle portions are in parallel relation.

The two members 10 and 11 are formed of steel, preferably, or of any other suitable resilient material and consequently there is enough spring in the material forming the handle portions 16a and 16b to allow the portion carrying the recess 25 to spring outwardly or ride over the button 26 until the button comes into position to enter the recess whereupon the resiliency of the portion will cause it to move back into place in parallel relation with the opposing handle portion.

Between the portions 10' and 11', making up the head 15, a clearance space 27 is provided, of sufficient width to receive a double-edged safety razor blade, so that when such blade is placed in position upon that face of the head portion 10' carrying the lugs 20 and the two portions of the head are swung into parallel relation so that the inclined or beveled edge 28 of the shorter head portion 10' engages under the undercut edge 13, the blade will be tightly gripped between the two head portions and due to the undercut of the edge 13 and the engagement thereagainst of the beveled edge 28, the two head portions are effectively held against separation. Since the co-acting edges 13 and 28 are also disposed obliquely across the head it will be seen that in bringing the two head portions into closed position they will be automatically stopped when they reach a parallel relation.

Due to the tapering thickness of the portions 10' and 11' of the head 15, which thickness also tapers off to the thickness of the members 10 and 11 through the handle portion, adjacent to the pivot 14, it will be seen that each side of the holding device has an inclined surface, here designated 29, against which a finger of the hand may rest when using the blade holder as a knife or for the stropping of a blade.

In Figure 2 a blade is shown in position and is designated 30 and in Figure 3 such blade is shown in broken lines. It will be readily apparent that by providing a relatively wide amount of material between the forward edge of the head and the lugs 20 there will not be such an excessive amount of blade exposed as to make its use as a

cutting element impractical or difficult. Also by tapering the two sides of the head and extending the cutting edge of the blade to the proper extent the blade will be maintained at the proper angle for sharpening or stropping when the device is moved over the surface of a strop with the inclined outer side of the head in position thereon.

We claim:

1. A razor blade holder comprising two relatively long members of approximately equal length having opposing flat inner faces and disposed in parallel juxtaposition when in use, a pivot coupling between the members substantially upon the longitudinal centers of the same and substantially midway between the ends, said members being of materially greater width than thickness, means forming an interlocking connection between two adjacent ends of the members, the portion of the two members between the interlocking means and the pivot forming a head which is tapered in thickness from one longitudinal edge to the opposite edge, one of the members in the head portion having a pair of recesses formed in the longitudinal edge thereof at the thinner edge of the head, a pair of lugs carried by the other member in the head portion and projecting from the inner face thereof and formed to enter said recesses, the head portion being wider than the portion of the members at the opposite side of the pivot from the head, the portions of the members lying between the pivot and the ends thereof remote from the head together forming a hand grip, each of the last named ends of the members having an end edge extending obliquely across the width thereof to form a tapering tail piece, the oblique end edge of one member crossing the oblique end edge of the other member whereby the application of compressive force against the remote outer edges of the members at the tail pieces effects the relative pivotal movement of the members about said pivot and the separation of the two portions of the members through the head end of the device, and means interposed between said opposing flat faces for yieldingly maintaining the members in parallel relation.

2. A blade holding device of the character stated in claim 1, in which said yieldable means comprises a relatively flat button formed upon one of the said opposing flat faces and a recess formed in the other opposing flat face to receive the button, the said members being of a character to have sufficient resiliency to be sprung apart for the passage of the button across the opposing member face for engagement in or disengagement from the recess.
